UNITED STATES PATENT OFFICE.

WILLIAM M. SMITH, OF MERIDEN, CONNECTICUT, ASSIGNOR TO MERIDEN BRITANNIA COMPANY, OF SAME PLACE.

DESIGN FOR A COFFIN-SCREW.

SPECIFICATION forming part of Design No. 15,672, dated December 30, 1884.

Application filed November 24, 1884. Term of patent 14 years.

To all whom it may concern:

Be it known that I, WILLIAM M. SMITH, of Meriden, in the county of New Haven and State of Connecticut, have invented a new Design for a Coffin-Screw; and I do hereby declare the following, when taken in connection with accompanying drawings and the letters of reference marked thereon, to be a full, clear, and exact description of the same, and which to said drawings constitute part of this specification, and represent, in--

Figure 1, a side view; Fig. 2, a view showing the outline of the base and cap; Fig. 3, a vertical central section.

This design relates to the head or exposed portion of the fastening device by which the top of a coffin is secured, commonly called "coffin-screws." These consist of a base and a tip, the tip forming the head of the screw; and the invention consists in the configuration and ornamentation of the head, as shown in the accompanying illustration.

A is the base, which is of elliptical form,

gradually rising in a curved line from the periphery toward the center. The surface of the base has the representation of leaves thereon. B is the head of the screw, which in horizontal outline is elliptical, the edge curving upward toward the center and terminating in a tip, C. The cap proper represents leaves as springing from the center and drooping downward. The tip represents leaves in a bud-like form on the center top of the cap. The tip C may be omitted without departing from the general characteristics of the design. 35

I claim—

The design for a coffin-screw, consisting of an elliptical-shaped base, its surface curving from the periphery upward, and representing leaves as lying thereon, with the cap B representing leaves as drooping over the center of the base, as shown in the accompanying illustration. 40

WILLIAM M. SMITH.
